UNITED STATES PATENT OFFICE.

JOHN F. KING, OF WASHINGTON, DISTRICT OF COLUMBIA.

CASH-CARRIER AND FARE-COLLECTOR.

SPECIFICATION forming part of Letters Patent No. 249,368, dated November 8, 1881.

Application filed August 15, 1881. (No model.)

To all whom it may concern:

Be it known that I, JOHN F. KING, a citizen of the United States, residing at Washington, in the District of Columbia, have invented new 5 and useful Improvements in Cash-Carriers or Fare-Collectors, of which the following is a specification.

This invention relates to an automatic cash-carrier or fare-collector, adapted, when applied 10 to a street-car, to be placed under the control of the driver, so that it can be operated to carry the fares from the passengers to the driver, and also to return change or tickets from the driver to the passengers, thereby avoiding the 15 necessity of the driver leaving the front platform of the car or the passengers getting up from their seats. It is also applicable to banks or stores, the apparatus in the last-named instance being placed under the control of the 20 cashier or other employé to whom and from whom notes, cash, papers, and the like can be conveyed by the carrier, which will pass over the several desks or counters of the establishment.

25 The object of my invention is to improve the construction and arrangement of the operating mechanism of the carrier, whereby the latter can be readily caused to travel to the several required localities in a path sufficiently elevated to prevent accidental collision of the carrier with persons in the car or room in which the carrier is located, and so that when arriving at the point where a fare is to be collected or other article to be placed on the carrier, the 30 same can be readily lowered to within convenient reach of the party. These objects I attain by means of the mechanism illustrated in the accompanying drawings, in which—

Figure 1 is a side elevation of a street-car 40 with my improved apparatus applied thereto. Fig. 2 represents detached sectional parts of the apparatus. Fig. 3 is an enlarged perspective view of the carrier or receptacle for receiving cash, tickets, and the like. Fig. 4 illustrates the apparatus arranged for a bank or store. Fig. 5 is an enlarged view, partly in section, of a portion of the apparatus used in the said bank or store; and Fig. 6 is a vertical section through the track, taken through the 45 carriage and track shown in Fig. 5.

Referring, now, to Figs. 1, 2, and 3, repre-

senting the apparatus as applicable to a street-car, the letter A indicates the street-car, of ordinary construction, and B the carrier box or receptacle, adapted for receiving and conveying 55 the fares, tickets, and change from one end of the car to the other. This carrier consists of a light box made partly of wood, glass, and tin or other suitable material, and formed with a slot, b, in its top, through which the fares can 60 be dropped by the passengers. It will also be provided with a hinged or sliding door, so that access can be had to its interior by the driver, and under some circumstances by the passengers when change is to be returned by the 65 driver; or the door can be locked by a key retained by the driver, and the change to be returned placed in one of the outer compartments of a tray, C, located at the base of the carrier-box.

The carrier-box is suspended within the car by means of a cord or cords, D, arranged to pass over the pulleys E, and thence forward to a large pulley-wheel supported over the front platform of the car. The pulleys E, over which 70 such cord or cords pass, are mounted in a movable carriage, F, that is arranged within a hollow track, G, secured to the ends of the car and located centrally near the top thereof, so as to be out of the way. This hollow track has a 75 longitudinal slot, g, extending nearly its entire length, so that the cords suspending the carrier-box can pass through the slot, and also so that the downwardly-projecting guides g' of the carriage can pass through the same. 80

The pulley-wheel H, which is at the front 85 end of the car, and to which the cords suspending the carrier-box are attached, is mounted loosely upon a fixed shaft, I, that is rigidly secured to that portion of the car-roof which extends over the front platform. This pulley-wheel is supported on the fixed shaft by means of a spring, K, that is coiled around the shaft, so as to lie within the hollow hub k of the pulley-wheel, the lower end of the spring resting 90 upon a flange, k', at the lower end of the shaft, and bearing upwardly against a shoulder formed in the hub of the pulley. The hub or pulley is provided with a crank-handle, L, within 95 convenient reach of the driver, so that by turning the handle, and consequently the pulley-wheel, the cord or cords can be wound upon 100

or unwound from the grooved pulley, thus elevating or lowering the carrier-box, according to the direction in which the pulley is turned. As a means for causing the carrier-box to travel back and forth through the car, I provide a second grooved pulley-wheel, M, loosely mounted upon the fixed shaft above the pulley that is employed for raising or lowering the carrier-box. One end of the cord m, passing around the upper pulley, connects with the forward end of the carriage within the hollow track, while the remaining end of said cord passes around a small pulley, m', at the rear end of the track, and thence to the rear side of the carriage, with which it is then connected; hence by rotating the upper pulley on the fixed shaft in one direction the carriage will be advanced or moved toward the front end of the car, and by a reverse movement of the said pulley the carriage will be drawn back.

In order to admit of the lower pulley being connected with the upper pulley, in order to operate the latter, I provide the upper side of the lower pulley with studs N, and form in the under side of the upper pulley recesses n for receiving said studs, whereby the two pulleys can be clutched when desired.

In order to simply raise and lower the carrier-box, the driver will grasp the crank-handle and before turning the same pull down upon it in order to unclutch the lower from the upper pulley, and by then turning the crank-handle the lower pulley will alone be turned, the upper pulley not being free to descend and engage the lower one by reason of a shoulder, n', on the fixed shaft. When the lower pulley is released, however, it will be raised by the action of the spring, so as to clutch with the upper pulley. If the crank-handle is now turned while these two pulleys are thus connected, the carriage will be moved along the track, and the carrier-box consequently carried through the car. During such movement the carrier-box will obviously not be raised or lowered, since if, for example, the carriage and box are being moved from the rear toward the front end of the car, the lower pulley will simply take up the carrier-box, suspending cord D in proportion to the distance traveled by the carriage, thus maintaining the latter at the same height. In this way the carrier-box can be caused to travel through the car above the heads of the passengers, and also lowered to collect fare whenever desired. Pulleys D' D' will be arranged at the forward end of the car for the cords to pass over, so as to properly guide the same.

In employing this apparatus in a bank or store, the slightly-modified construction illustrated in Figs. 4, 5, and 6 will preferably be used. In this instance the carrier-box B is supported by a swinging bar, P, that is provided at its upper end with a yoke or bail, p, embracing the track and the carriage F and hinged to the sides of the carriage. The hollow track G is formed with the longitudinal

slot g through its upper side, through which a vertical guide-bar, g', extends into the hollow track, and upon the lower end of this guide-bar is a short half-round bar, g'', arranged within the track so that its convex side will lie against the upper portion of the inner wall of the track, as shown in Figs. 5 and 6. The cord m, for causing the carriage to travel along the track, is arranged within the same and connected with the carriage as before, while the cord D, for swinging the pivoted bar so as to raise or lower the carrier-box, passes from the hollow track up through the carriage and connects with the upper end of the pivoted bar. The mechanism for operating these cords is the same as that shown in connection with the apparatus employed for a street-car, and hence need not be further described.

The carriage shown in Figs. 4, 5, and 6 is outside of and over the track, and is provided at its ends with grooved wheels R, which rest upon the track, whereby the carriage can be easily moved and with but little friction.

In Fig. 4 I have shown a cashier's desk, S, and a long counter, T, over which the track is arranged, whereby money, papers, or other articles can be readily carried back and forth between the several employés and the cashier, and the apparatus be under the control of the latter. The track can be secured to the wall or to the ceiling by suitable ornamental brackets, and in such position that one terminus thereof will be over the cashier's desk.

In the apparatus illustrated in connection with a street-car, there will be sufficient friction between the sliding carriage and the track to prevent the carriage from being drawn forward when the cord is wound upon the lower pulley-wheel in order to elevate the carrier-box; but when the carriage is supported upon wheels or rollers, as shown in the apparatus described, for use in a bank or store, the carriage will be apt to be drawn forward under the aforesaid circumstances, since the cord for vibrating the pivoted lever-bar is attached to the short upper end thereof, and consequently the tension required to raise the weight would be likely to also drag the carriage. To obviate this I pivot to the lower part of the carriage-frame, which extends below the tube or hollow track, a pawl, U, and connect the outer end thereof by a cord, V, with a spring, V', attached to the upper portion of the carriage at such point that the cord will be at an angle, as shown in Fig. 5. Upon one side of the pivoted bar, above its pivot, I arrange a stud, V³, so that when the bar is turned, by drawing upon its upper end, the stud will strike the cord, and, pressing the same out of a right line, lift the pawl into engagement with a line of rack-teeth on the under side of the hollow track. The circular path in which the stud moves is indicated by dotted lines, and it will be evident that after the stud has moved about half a circle it will leave the cord so that the pawl can again drop. If desired, two cords and studs in opposite sides of the car-

riage might be used, although generally one of each will be sufficient.

Instead of the rack-teeth, the pawl can be tipped with rubber, which will subserve the same purpose; and instead of the mechanism shown, other checking devices might obviously be employed.

Having thus described my invention, what I claim is—

10 1. An automatic cash-carrier or fare-collector comprising a carrier-box arranged to be raised and lowered and carried back and forth and also to be arrested at any desired point in its line of travel at the will of the operator, in combination with mechanism extending to the operator's stand at the end of the line for effecting such movement on the part of the carrier-box, substantially as described.

20 2. An automatic cash-carrier or fare-collector comprising a carrier-box arranged to be raised or lowered and also carried back and forth at the will of the operator, in combination with mechanism extending to the operator's stand at the end of the line for effecting such move- 25 ments on the part of the carrier-box, substan-

tially as described.

30 3. The combination, with the elevated track, of the carriage arranged to traverse the same, the carrier-box suspended from the carriage, and the independent pulley-wheels connected by cords to the carrier-box and carriage, said pulley-wheels being arranged to be connected and operated conjointly, so as to cause the carriage

to traverse the track or to be disconnected and but one pulley-wheel operated, so as to effect 35 the raising or the lowering of the carrier-box, substantially as described.

4. The combination of the elevated track with the carriage arranged to traverse the same, the carrier-box suspended from the carriage, the 40 lower pulley-wheel, H, loosely mounted upon a fixed shaft and connected by a cord with the carrier-box, the upper pulley-wheel, M, loosely mounted upon the said fixed shaft and connected by a cord with the carriage, the studs upon 45 the lower pulley-wheel received into recesses in the upper pulley-wheel, and the spring within a hub of the lower wheel arranged to force the same upward to connect the two pulley-wheels, substantially as described. 50

5. The combination, with the elevated track, of the carriage arranged to traverse the same, the carrier-box suspended from the carriage, the mechanism for causing the carriage to traverse the track and for raising and lowering the 55 carrier-box, and the check mechanism for preventing the motion of the carriage while the carrier-box is being elevated, substantially as described.

In testimony whereof I have hereunto set 60 my hand in the presence of two subscribing witnesses.

JOHN F. KING.
